UNITED STATES PATENT OFFICE

161,470

BURIAL VAULT

Edward J. Lager, Davenport, Iowa

Application December 3, 1949, Serial No. 6,400

Term of patent 7 years

(Cl. D19—1)

To all whom it may concern:

Be it known that I, Edward J. Lager, a citizen of the United States, residing at Davenport, in the county of Scott and State of Iowa, have invented a new, original, and ornamental design for a Burial Vault, of which the following is a specification, reference being made to the accompanying drawings, forming a part thereof.

In the drawings,

Fig. 1 is a perspective view of a burial vault, embodying my new design;

Fig. 2 is a plan view of the vault; and

Fig. 3 is an end view thereof.

The side and end of the burial vault not shown are the same, respectively, as the side and end shown.

I claim:

The ornamental design for a burial vault, substantially as shown and described.

EDWARD J. LAGER.
